UNITED STATES PATENT OFFICE

FRANK H. COLE, OF CHELSEA, MASSACHUSETTS

BOILER TUBE CLEANER

Application filed December 29, 1930. Serial No. 505,405.

This invention relates to boiler tube cleaners and is more especially concerned with cleaners of the general type disclosed in my co-pending application Serial No. 308,300, filed September 25, 1928.

The cleaner shown in said application comprises a nozzle head with connections for conducting steam to it, a series of nozzles projecting from said head and arranged to be aligned with the boiler tubes, and means for traversing said head and the nozzles carried thereby to direct jets of steam into the tubes and thus to blow the soot and ash out of them. This mechanism has proved exceptionally satisfactory in practice and the present invention aims further to improve and perfect boiler tube cleaners of this general type with a view especially to facilitating the installation of the cleaner, and reducing the expense of manufacture.

The nature of the invention will be readily understood from the following description when read in connection with the accompanying drawings, and the novel features will be particularly pointed out in the appended claims.

In the drawings,

Figure 1 is a front elevation of a boiler cleaner constructed in accordance with this invention;

Fig. 2 is a vertical, sectional view of the apparatus shown in Fig. 1;

Fig. 3 is a perspective view illustrating details of construction;

Figs. 4 and 5 are transverse, longitudinal and sectional views, respectively, of parts of the mechanism for traversing the nozzle head; and

Fig. 6 is an elevation, partly in section, illustrating the relationship between the thrust bar and the nozzle head.

The boiler cleaner is shown installed in a fire tube boiler of a common type comprising a casing 2, a tube sheet 3, fire tubes 4, and smoke box 5. The nozzle head is indicated at 6 and it carries a vertical series of nozzles 7 which are located, respectively, in the horizontal planes of the center lines of the tubes. Steam is conducted to the head 6 through a series of pipe connections 8 which are pivoted

together so as to permit the traversing movement of the head 6, the flow of steam through these connections being controlled by a supply valve (not shown) which is customarily located outside of the boiler casing. In this respect the arrangement may be similar to that disclosed in my prior patent No. 1,636,355.

The nozzle head 6 depends vertically from, and is supported by, a slide 10 to which the flexible steam conducting pipe 8 also is connected. This slide is mounted to run on a track 12 which preferably consists of a channel bar supported in an inverted position,—that is, with its grooved side downward. Side pieces 13—13 are bolted to the opposite sides of the slide 10 and are bent over at their upper ends to rest on the upper flat surface of the track or channel bar 12 so that the slide 10 is, in effect, suspended on the track.

For the purpose of traversing the slide 10 and nozzle head 6, a screw threaded shaft 14 is located horizontally in the groove of the channel bar 12, one end of this shaft being supported in a bearing block 15, Fig. 1, 75 mounted at one end of the channel bar, while the opposite end projects through the boiler casing 2. This shaft operatively engages an internally threaded block or nut 16, Figs. 4 and 5, which is provided with lugs 17—17 that extend into sockets in the slide 10 so that the slide is compelled to move in unison with the block 16. These parts 10, 13 and 16 may be said to form a carriage on which the nozzle head is supported. At a point outside the boiler casing the shaft 14 is equipped with a sprocket wheel 18 over which a chain 19 runs for the purpose of enabling a workman to revolve the shaft. This motion of the shaft operates through the nut 16 to traverse the carriage 10 and nozzle head 6 backward and forward, the direction of movement of these parts depending upon the direction of rotation of the shaft. During this movement the edges of the parts 13—13 ride on the upper surface of the track 12, as will be obvious from an inspection of Fig. 4.

It may here be pointed out that the track or channel bar 12 protects the entire threaded section of the shaft from soot or ashes drop-

ping on it from above. Preferably, also, the block 16 is provided at its opposite ends with extensions 20—20, Fig. 5, which engage the threads and act as wipers to clean the threads before they enter the main screw threaded section of the block.

An important feature of this invention resides in the supporting mechanism for the cleaner. The preferred arrangement comprises two brackets 21—21, Figs. 1 and 3, bolted or riveted to the upper side of the track 12 and supported by additional bracket members 22—22 which are themselves secured rigidly to two sleeves 23—23 which extend into the boiler tubes 4. Each of the brackets 22 includes a curved piece 24 which is welded or otherwise permanently secured to its respective sleeve 23. Each sleeve has a tapered split extending longitudinally thereof and the sleeve is secured in one of the boiler tubes 4 by driving a wedge 25, Fig. 3, into the split in the tube and thus expanding the sleeve firmly into engagement with the wall of the tube. While these parts secure the brackets permanently to the boiler they can, nevertheless, be removed by driving out the wedge 25.

This arrangement greatly reduces the time, labor, and expense involved in installing the cleaner in a boiler.

In addition to supporting the track the sleeves 23—23 may also be made to support part, at least, of the weight of the pipe connections 8 which conduct steam to the nozzle head. An arrangement suitable for this purpose is shown in the drawings. It comprises two angle bars 26—26 bolted or riveted at their lower ends to the respective brackets 21—21 and secured at their upper ends to a fitting 27, Fig. 2, which forms part of the pipe connections. The nature of the jointed sections immediately adjacent to the fitting 27 is such that the steam line may be led into the smoke box either through the front wall of said box or through the side wall.

In using the cleaner the workman first opens the valve controlling the admission of steam to the pipe connections 8 and then by pulling on the chain 19 he revolves the shaft 14 and thus traverses the nozzle head 6 across the ends of the tubes 4. As the nozzles come into line with the vertical rows of tubes they direct steam through the tubes, thus blowing the soot and ash out of them. When the head reaches the limit of its traverse in one direction the workman then reverses the rotation of the shaft 14, thus reversing the direction of traverse. The nozzle head 6 is equipped with a pivoted tip 28 which normally is held substantially in alignment with the nozzle by springs 29, but which swings when it strikes the side of the boiler casing to permit the cleaning of all of the tubes in the tube sheet, as explained more fully in my earlier patent above designated.

The jets of steam issuing from the nozzle

create a certain amount of back pressure tending to swing the nozzle head 6 on the track 12 in a clockwise direction, as seen in Fig. 2. In order to support the head against this tendency, the carriage is provided with a lug 30, Figs. 2 and 4, which engages the inner surface of one flange of the channel bar 12 and cooperates with the parts 13—13 to grip the track and thus prevent any substantial swinging movement of the nozzle head. In addition to this arrangement it is sometimes preferable, particularly in boilers of large diameter, to install a thrust bar 31, Figs. 1, 2 and 6, where it will back up the lower part of the nozzle head as the head moves backward and forward across the tube sheet. This bar 31 may conveniently consist of an angle iron and may be secured in place by brackets 32—32, Fig. 1, bolted to the casing.

As above stated, the installation expense is substantially reduced by the peculiar mounting shown and described. It should also be noted that the sleeves 23 do not obstruct the tubes in which they are located to any substantial degree and these tubes, as well as the others, are cleaned effectually by the jets of steam. The channel bar 12 sheds the ash and soot and affords protection both for the screw threaded section of the shaft 14 and also for the nut 16. The construction of these parts is such that the manufacturing operations may be performed very economically. The cleaner may be used in a great variety of sizes and makes of fire tube boilers, suitable changes being made in the design to adapt it to the requirements of individual installations.

While I have herein shown and described a preferred embodiment of my invention, it will be understood that the invention may be embodied in a considerable variety of forms without departing from the spirit or scope thereof.

Having thus described my invention, what I desire to claim as new is:

1. In a fire tube boiler, the combination of a tube sheet and tubes supported therein, of a tube cleaner, and supporting means for said cleaner comprising devices permanently anchored in certain of the boiler tubes, said devices being so constructed and arranged as to leave the last mentioned tubes open for the cleaning operation.

2. In a fire tube boiler, the combination of a tube sheet and tubes supported therein, of a tube cleaner, brackets for supporting said cleaner, and devices anchored in certain of the boiler tubes and serving to support said brackets, said devices being so constructed and arranged as to leave the last mentioned tubes open for the cleaning operation.

3. In a fire tube boiler, the combination of a tube sheet and tubes supported therein, of a tube cleaner comprising a movable head carrying one or more nozzles for directing

jets of steam into the boiler tubes, connections for conducting steam to said head, and means anchored in the boiler tubes for supporting said cleaner, said means being so constructed and arranged as to leave the last mentioned tubes open for the cleaning operation.

4. A construction according to preceding claim 3 characterized by the fact that said supporting means includes a split sleeve extending into a boiler tube, and means for expanding said sleeve into firm engagement with the wall of said tube.

5. A construction according to preceding claim 3 characterized by the fact that said supporting means includes a split sleeve extending into a boiler tube, and a wedge driven into the split in said sleeve for expanding said sleeve into firm engagement with the wall of said tube.

6. In a fire tube boiler, the combination of a tube sheet and tubes supported therein, of a tube cleaner comprising a movable head carrying a plurality of nozzles for directing jets of steam into the boiler tubes, connections for conducting steam to said head, a track on which said head is supported for movement, means for traversing said head on said track to carry said nozzles across the ends of said tubes, and means including devices anchored in the boiler tubes for supporting said track, said devices being so constructed and arranged as to leave the last mentioned tubes open for the cleaning operation.

7. In a fire tube boiler, the combination of a tube sheet and tubes supported therein, of a tube cleaner comprising a movable head carrying a plurality of nozzles for directing jets of steam into the boiler tubes, connections for conducting steam to said head, a track, a carriage mounted on said track and supporting said head for traversing movement, means for traversing said carriage on said track, and means including devices anchored in the boiler tubes for supporting said track, said devices being so constructed and arranged as to leave the last mentioned tubes open for the cleaning operation.

8. In a boiler, a tube cleaner comprising the combination of a nozzle head, a carriage supporting said head, means for conducting steam to said head, a screw threaded shaft mounted in the smoke box of the boiler, an internally threaded block mounted on said carriage for movement therewith and engaging the threads of said shaft, a channel bar supported in said smoke box and forming a track on which said carriage is supported for traversing movement, said shaft being located in the channel of said bar, and means operable to rotate said shaft to traverse said head on said track, said head having parts secured thereto and engaging said track to suspend the head thereon.

9. A boiler tube cleaner according to preceding claim 8 in which said carriage is provided with a lug cooperating with said channel bar to resist the tendency of the carriage to swing on said bar due to back pressure of the steam issuing from said nozzles.

10. A boiler tube cleaner according to preceding claim 8 in which the carriage includes removable side pieces for running on the track and said screw threaded block is removably mounted on said carriage.

11. In a fire tube boiler, the combination with a boiler tube, of a supporting device comprising a sleeve extending into said tube, and means for expanding said sleeve into firm engagement with the wall of the tube while leaving a substantial part of the diameter of the tube open for the passage of gases therethrough.

12. In a fire tube boiler, the combination with a boiler tube, of a supporting device comprising a split sleeve extending into said tube, and a wedge driven into the split in said sleeve and serving to expand the sleeve into firm engagement with the wall of the tube.

13. In a fire tube boiler, the combination with a boiler tube, of a supporting device comprising a bracket, a split sleeve on which said bracket is mounted, said sleeve extending into a boiler tube, and a wedge driven into the split in said sleeve and serving to expand the sleeve into firm engagement with the wall of the tube.

14. In a fire tube boiler, the combination of a tube sheet and tubes supported therein, of a tube cleaner, and means for supporting said cleaner permanently in position to operate on a series of said tubes, said means including supporting devices permanently anchored in certain of the boiler tubes, said devices being so constructed and arranged as to leave the last mentioned tubes open for the cleaning operation.

CERTIFICATE OF CORRECTION.

Patent No. 1,877,267.

September 13, 1932.

FRANK H. COLE.

It is hereby certified that error appears in the printed specification of the above numbered patent requiring correction as follows: Page 2, line 43, for the misspelled word "ront" read front; page 3, line 32, claim 6, after "track" and before the comma insert the words permanently in its operative position; and that the said Letters Patent should be read with these corrections therein that the same may conform to the record of the case in the Patent Office.

Signed and sealed this 22nd day of November, A. D. 1932.
